[57] CLAIM

The ornamental design for adjustable luggage carrier cross rails with locking wrench, as shown and described.

DESCRIPTION

FIG. 1 is a perspective view of an adjustable luggage carrier cross rail with locking wrench showing our new design, it being understood that the broken lines are for illustrative purposes only and form no part of the claimed design;

FIG. 2 is an enlarged fragmentary top plan view of one end thereof;

FIG. 3 is an enlarged fragmentary cross-sectional view taken along the lines 3—3 in FIG. 2;

FIG. 4 is a greatly enlarged fragmentary cross-sectional view taken along the lines 4—4 in FIG. 2;

FIG. 5 is a greatly enlarged end elevation view thereof, the opposite end being a mirror image of that shown; and

FIG. 6 is a greatly enlarged fragmentary bottom plan view of FIG. 2.
